UNITED STATES PATENT OFFICE.

HENRY P. CLAUSEN, OF MOUNT VERNON, NEW YORK, ASSIGNOR, BY MESNE ASSIGNMENTS, TO WESTERN ELECTRIC COMPANY, INCORPORATED, A CORPORATION OF NEW YORK.

TELEPHONE-EXCHANGE SYSTEM.

1,232,497.

Specification of Letters Patent. Patented July 10, 1917.

Application filed October 21, 1915. Serial No. 57,069.

To all whom it may concern:

Be it known that I, HENRY P. CLAUSEN, a citizen of the United States, residing at Mount Vernon, in the county of Westchester 5 and State of New York, have invented certain new and useful Improvements in Telephone-Exchange Systems, of which the following is a full, clear, concise, and exact description.

10 This invention relates to improvements in telephone exchange systems, and has for its principal object to provide means for rendering more efficient and satisfactory service in the handling of calls that are abandoned 15 by a calling subscriber before the subscriber who is being called has answered.

In accordance with one feature of this invention, the link circuits at a telephone switchboard are equipped with a retarder 20 circuit-controlling device which delays the operation of disconnect signals until a predetermined time after an incompletely call has been abandoned by a calling subscriber.

According to another feature of this invention, characteristic signaling effects are produced on the supervisory signals at certain stages in the operation of the system to indicate to the operator immediately the condition of the connections.

30 This invention is illustrated diagrammatically in the drawing, in which complete station and switchboard equipment for two central-energy subscribers' telephone lines, of a well-known type, are respectively indicated by the numerals 1 and 2. A link circuit, indicated at a switchboard position 3, adapted to connect the stations 1 and 2 for communication, is equipped with a thermal relay 55 suitable for illustrating the features of this 40 invention.

In describing the operation of this system, let it be assumed that a subscriber at the station 1 desires to communicate with a subscriber at the station 2. Removal of the 45 receiver from the switch-hook at station 1 causes a line lamp 5 to be lighted through the operation of a line relay 4, in response to which an operator at the position 3 inserts an answering plug 9 of the link conductor 50 in the jack 7 of this calling line. The energization of a cut-off relay 6, listening relay 17 and a control relay 12 now take place over associated paths which may be traced from earth, winding of relay 6, signal cir- 55 60 65 70 75 80 85 90 95 100 105

cuit contacts 8 and 10 of the jack 7 and plug 9, respectively, thence branching, first, by way of conductor 11 and the winding of relay 12 to earth through the battery 60, and second, by way of conductor 16, winding of the relay 17, conductor 18, contacts 28 of a relay 30 through the battery 60 to earth. This answering connection also renders a supervisory relay 20 responsive to talking current, which is supplied from battery 60, through its windings, over the main or talking conductors to the telephone instrument at station 1. Although no operator's telephone set is shown in the drawing, it will be understood that the listening relay 17 is for the purpose of including such a telephone set with the talking conductors of this connection. In response to the request of the calling subscriber, the operator now inserts a calling plug 32 of the link circuit in a jack 34 of the line 2. A second control relay 30 and a cut-off relay 61, the latter associated with the line 2, are thereby energized by current from the battery 60 over a series circuit completed through the signal contacts 31 and 33 of the plug 32 and the jack 34, respectively. The cut-off relay 61 disconnects its associated line relay from the line circuit 2 and the contacts 28 of relay 30 disconnect the listening relay 17, thereby disconnecting the operator's telephone set (not shown) from the talking circuits of this connection. The relay 30 also closes a circuit through its contacts 29 to include a supervisory signal 36 on the battery 60, the further circuits of which may be traced from contacts 37 of a supervisory relay 38, conductor 39, contacts 41 of supervisory master relay 40, conductor 42, contacts 46 of a ringing relay 45, and contacts 51 of a trip relay 50 to earth. In order to ring the bell at station 2, the operator now momentarily depresses a key 53 thereby completing a circuit for the energization of relays 40 and 45. This circuit may be traced from the battery 60, contacts 22 of the relay 20, the right-hand winding of the relay 40, conductor 44, the winding of relay 45, conductor 52, to earth through the key 53. The contact members 48 and 49 of relay 45 open each side of the calling end of the link circuit toward the station 1, and connect a source of grounded ringing current (not shown), indicated as feeding through the trip relay

50, to the line circuit of the station 2. The closing of contacts 47 of relay 45 substitute an earth connection through the contacts 51 of the trip relay 50 for the earth connection 5 through the key 53 to retain the relays 40 and 45 after the key 53 has been released. The separation of contacts 46 of the relay 45 opens the circuit of the supervisory lamp 36, and the separation of contacts 21 of the 10 supervisory relay 20 opens the circuit of the supervisory lamp 15. Therefore, both of the supervisory lamps are extinguished during the period ringing current is being applied to the line circuit of the called subscriber. 15 With the circuits in the position just indicated, that is, relays 6, 12, 20, 30, 61, 40 and 45 energized, let it be assumed that the subscriber at station 1 decides not to wait for an answer from station 2, and accordingly abandons the call by replacing the receiver on the switch-hook. This results in cessation of talking current through the instrument at station 1, thereby deenergizing the supervisory relay 20. The separation of contacts 22 of the relay 20 releases the ringing relay 45 to disconnect the ringing current from the line circuit of station 2 and reestablish the talking circuit of the link conductors; and also prepares a circuit 25 through the contacts 46 of the latter relay for the supervisory lamps 15 and 36. Although the separation of the contacts 22 of relay 20 permits the release of the relay 45, the relay 40 is influenced by its copper secondary to remain energized until the contacts 23 of relay 20 are closed to complete a locking circuit from battery 60, the left-hand winding of relay 40, contacts 43 of this relay, and contacts 13 of relay 12 to earth. 30 The contacts 41 of relay 40 being retained separated, the winding 56 of the thermal relay 55 is energized by current jointly supplied through the circuits of the supervisory lamps 15 and 36. One of these circuits includes the battery 60, contacts 14 of the relay 12, the lamp 15, contacts 21 of the relay 20, and conductor 58 to a junction with conductor 39; the other circuit includes battery 60, contacts 29 of the relay 30, the lamp 36, 35 contacts 37 of the relay 38, and conductor 39 to the junction formed with conductor 58. From this junction the current from each path completes circuit through the winding 56 of the thermal relay 55, conductor 42, contacts 46 of the relay 45, and contacts 51 of the relay 50 to earth. The supervisory lamps 15 and 36 are not lighted to full brilliancy through the circuits just traced but are characteristically dimmed owing to 40 the current being reduced by the resistance of the winding 56 of the thermal relay 55. After a predetermined period, however, this current produces sufficient heat in the winding 56 of the thermal relay to expand the member 58 longitudinally to close its con-

tacts 57, thereby including a low resistance locking winding 59 of the thermal relay in bridge on its first winding 56. This reduction in the resistance of the lamp circuits permits additional current therethrough, 70 and the illumination of the lamps 15 and 36 is now increased to full brilliancy, which constitutes a disconnect signal.

In describing further characteristic signaling effects on the supervisory signals, 75 attention is directed to that point in the foregoing description at which a call had been abandoned by a calling subscriber, at which moment the relays 6, 12, 30, 40 and 61 are retained operated. The supervisory lamps 15 and 36 are only dimly lighted, and current action in the winding 56 of thermal relay 55 is taking place as described. Now, in case the receiver is removed from the switch-hook at station 2, the supervisory 80 relay 38 is operated, thereby completely extinguishing the supervisory lamp 36 by the separation of contacts 37, and the supervisory lamp 15 is lighted at full brilliancy over the contacts 35 of relay 38 to the earth 90 connection, as the contacts 35 establish a short circuit through conductor 39, which embraces the winding 56 of relay 55, conductor 42, contacts 46 of relay 45 and contacts 51 of relay 50. In case the switch-hook is now intermittently operated at station 2, the supervisory lamp 15 will flash from dim to full illumination, while the supervisory lamp 36 will flash from dim to entire absence of light. This flashing signal is further distinctive in that the lamps respond in partially opposite phase. That is, when lamp 15 is brilliantly lighted, lamp 36 is entirely extinguished, both lamps being dimmed at the same instant. 95

Let it be further assumed that the calling subscriber instead of the called subscriber, intermittently operates the switch-hook at station 1 immediately after having first abandoned the call. Successive openings of contacts 23 of the supervisory relay 20, in response to such intermittent operation of the switch-hook, would not permit the release of the lagged relay 40. Therefore, at each interruption of the contacts 21 of the supervisory relay 20, supervisory lamp 15 is entirely extinguished, while at the same instant illumination of the supervisory lamp 36 is proportionately increased due to the ratio of current change in the winding 110 56 of thermal relay 55, resulting from the cessation of current otherwise supplied through this winding from the circuit of the lamp 15. The lamp 15 is accordingly flashed from dim to being completely extinguished, while the lamp 36 is flashed from dim to increased illumination. If, instead of the switch-hook being intermittently operated at station 1, the receiver is retained off the switch-hook immediately after a call 115 120 125 130

- has been abandoned, relay 40 will be restored due to the separation of contacts 23 of supervisory relay 20. Contacts 41 of relay 40 now short-circuit the winding 56 of the thermal relay 55, thereby rendering each of the supervisory lamps 15 and 36 responsive to the respective line circuit with which the associated ends of the link circuit may be joined.
- 5 10 On completed connections, that is, when a called subscriber answers while the instrument is retained in the talking position at the calling station, the contacts 41 of the relay 40 establish a short circuit on the winding 56 of the thermal relay 55, and each supervisory lamp 15 and 36 accordingly remain under the control of their respective supervisory relays 20 and 38. To briefly describe the operations which take place on 15 such completed connections, let it be assumed that the operations of a connection have been carried to the stage already described, as the moment before the calling subscriber abandoned the call. Accordingly, the relays 6, 12, 20, 30, 61, 40 and 45 would be energized. Now, when the call is answered by the removal of the receiver from the switch-hook at station 2, the increased quantity of ringing current, permitted through the winding of the trip relay 50 by the comparatively low resistance of the talking circuits at station 2, operates the relay 50, and the separation of its contacts 51 opens the circuits of the relays 40 20 and 45, thereby permitting these relays to restore. Separation of the contacts 47 of relay 45 prevents a reoperation of the relays 45 and 40 over the first circuit traced, and the separation of the contacts 23 of the supervisory relay 20 prevents the completion of the locking circuit, as previously traced, through the left-hand winding of relay 40. Talking battery is supplied to the instrument at station 2 through the windings of 25 the supervisory relay 38. The condenser shown in each talking conductor of the link circuit is for the purpose of preventing interference between the answering and calling supervisory signals by separating the 30 battery supply circuits of connected subscribers.
- Although a thermally operated relay has been illustrated and described in this invention, it will be understood that any form of 35 mechanically retarded circuit-controlling device, dash-pot relay or similarly suitable device, may be substituted for the thermal relay without departing from the purpose of this invention.
- 50 40 While a plurality of batteries have, for convenience, been shown in the drawing, such batteries may be and preferably are one and the same battery.
- 45 What is claimed is:
- 55 1. A telephone exchange system comprising

ing a calling and a called telephone line, a link circuit connecting the lines, a supervisory signaling device for the link circuit, an operating circuit for the signaling device completed upon the restoration to the switchhook of the receiver at the calling station before the removal of the receiver from the switchhook at the called station thereby causing the signaling device to furnish a signal of one indication, and a circuit changing device for altering the condition of the operating circuit at the expiration of a predetermined period thereby causing the signaling device to furnish a signal of another indication.

2. A telephone exchange system comprising a calling and a called telephone line, a link circuit connecting the lines, a supervisory relay for each end of the link circuit, a signaling device controlled by each relay, an operating circuit for the signaling device completed upon the deenergization of the answering supervisory relay before the calling supervisory relay has been energized thereby to cause the signaling device to furnish signals of one indication, and a circuit changing device for altering the condition of the operating circuit at the expiration of a predetermined period thereby causing the signaling device to furnish a signal of another indication.

3. A telephone exchange system comprising a calling and a called telephone line, a link circuit connecting the lines, a supervisory signaling device for the link circuit, an operating circuit for the signaling device completed upon the restoration to the switchhook of the receiver at the calling station before the receiver at the called station is removed from its switchhook thereby to cause the signaling device to furnish a signal of one indication, and a circuit changing switch for decreasing the resistance of the operating circuit at the expiration of a predetermined period thereby causing the signaling device to furnish a signal of another indication.

4. A telephone exchange system comprising a calling and a called telephone line, a link circuit connecting the lines, a supervisory relay for each end of the link circuit, a signaling device controlled by each relay, an operating circuit for the signaling device completed upon the deenergization of an answering supervisory relay before the calling supervisory relay is energized, and a circuit changing switch for decreasing the resistance of the operating circuit at the expiration of a predetermined period thereby causing the signaling device to furnish a signal of another indication.

5. A telephone exchange system comprising a calling and a called telephone line, a link circuit connecting the lines, a supervisory signaling device for the link circuit,

4

an electrically operated circuit changing switch, an operating circuit for the signaling device including the circuit changing switch completed upon the restoration to the switchhook of the receiver at the calling station before the receiver at the called station has been removed from the switchhook thereby causing the signaling device to furnish a signal of one indication, and a resistance connected in parallel with the circuit changing switch by the operation thereof at the expiration of a predetermined period to reduce the resistance of the operating circuit thereby causing the signaling device to furnish a signal of another indication.

6. A telephone exchange system comprising a calling and a called telephone line, a link circuit connecting the lines, a supervisory relay for each end of the link circuit, a signaling device controlled by each relay, an operating circuit for the signaling devices, a third relay when energized cooperating with the supervisory relays when deenergized to complete the operating circuit through the signaling devices thereby causing said devices to furnish a signal of one indication, and a circuit changing switch subsequently operated to alter the condition of the operating circuit thereby causing the signaling devices to furnish a signal of another indication.

7. In a telephone exchange system, a plurality of telephone stations, link circuits for interconnecting said telephone stations, supervisory signals for said link circuits, a retarder circuit-controlling device for altering the character of the indications of said supervisory signals, and means, rendered operative when a call is abandoned by a calling subscriber, before the station called has answered, for rendering said retarder circuit-controlling device effective.

8. In a telephone exchange system, a plurality of telephone stations, link circuits for interconnecting said telephone stations, supervisory signals for said link circuits, a retarder circuit-controlling device for al-

tering the character of the indications of said supervisory signals, and means, responsive when the circuits at two connected telephone stations are in the talking position, for rendering said retarder circuit-controlling device ineffective.

9. In a telephone link circuit, supervisory signals, supervisory relays for controlling the operation of said supervisory signals, and a circuit-controlling means for simultaneously causing one of said supervisory signals to display a positive indication and another one of said supervisory signals to display a negative signal in response to the operation of either one of said supervisory relays.

10. In a telephone link circuit, supervisory lamps, supervisory relays for controlling the operation of said supervisory lamps, and a circuit-controlling means for controlling said supervisory lamps to be dimly lighted for one position of either one of said supervisory relays and to cause one of said supervisory lamps to be brilliantly lighted in synchronism with the extinguishing of the other one of said supervisory lamps for the other position of either one of said supervisory relays.

11. In a telephone link circuit, supervisory lamps, supervisory relays for controlling the operation of said supervisory lamps, a circuit-controlling means for effecting said supervisory lamp to be dimly lighted for one position of either one of said supervisory relays and to cause one of said supervisory lamps to be brilliantly lighted in synchronism with the extinguishing of the other one of said supervisory lamps for the other position of either one of said supervisory relays, and a slow-acting relay cooperating with said circuit-controlling means and said supervisory relays to control such characteristic indications of said supervisory lamps.

In witness whereof, I hereunto subscribe my name this 16th day of October, A. D. 1915.

HENRY P. CLAUSEN.
